UNITED STATES PATENT OFFICE.

JOHN H. ELVERS, OF OWINGS MILLS, MARYLAND.

GAME APPARATUS.

1,051,718.

Specification of Letters Patent. Patented Jan. 28, 1913.

Application filed April 15, 1910. Serial No. 555,589.

To all whom it may concern:

Be it known that I, JOHN H. ELVERS, a citizen of the United States of America, residing at Owings Mills, in the county of 5 Baltimore and State of Maryland, have invented new and useful Improvements in Game Apparatus, of which the following is a specification.

This invention relates to game apparatus, 10 and has for an object to provide apparatus of this character which may be played with a view of furnishing a great amount of amusement.

In the drawing, forming a portion of this 15 specification and in which like numerals of reference indicate similar parts in the several views:—Figure 1 is a plan view of my improved game apparatus. Fig. 2 represents perspective views of certain of the 20 pieces.

My improved game apparatus comprises a board 1 on which is arranged a pictorial representation of a chart of the world, the 25 part 2 representing the "North Pole" or one goal of the apparatus. The said board has straight longitudinal side edges and arcuate and portions 5'. Merging outwardly from each of the arcuate ends of the game board are extensions, or what might be termed, in 30 connection with the game board, final goals 4. The board is divided to form two separate sets of playing surfaces 3, each of which is constructed to accommodate the playing pieces of two players. Each play- 35 ing surface is divided to form a set of ten spaces 7 and a set of ten spaces 9, the spaces 7 and 9 being separated from each other by the intermediate spaces 10. The said intermediate row of the spaces 10 divides the 40 groups or playing spaces 7 and 9 to one side of the axial line of the board and also provides communication for the spaces with one another, whereby, for instance, the player moving in spaces 7 is permitted to move in 45 a direction toward his opponent's spaces by first moving in one of the said spaces 10. Each playing surface is also formed to provide a series of spaces 16 which connect with the spaces 7 and 9 respectively, as 50 shown, and as illustrated, the spaces 7 and 9 are each connected with the goal 2 by the route forming spaces 17.

Ten pieces such as those illustrated at 10' 55 in Fig. 2 of the drawing are arranged in the spaces 7 of the playing surface and ten similar playing pieces 11 are arranged in the

spaces 9. Each piece 10' is provided preferably with a black surface 12 and a red surface 13. Each piece 11 is provided with a white surface 14 and a green surface 15. 60

The game is played very much on the order of the old and well known game of checkers, the respective players being allowed to move their men into each other's spaces but toward the goal 2 if possible with 65 a view to jumping each other, the object of each player being to move as many of his playing pieces as possible to the route forming spaces 17. After reaching the spaces 17 the player is allowed to move his playing 70 pieces to the goal, after which he is allowed in turn of the players to return to the playing spaces 7 and 9 and to move in turn to the final goal 4, care, of course, being exercised to avoid being jumped by an opponent. 75

In the initial starting of the game, the player at the left of the lower playing surface of the game board places ten men, such as shown at 10' in Fig. 2, in the spaces 7, arranging the men so that the black surfaces 80 thereof are exposed to view. The player at the right hand lower corner of the game board places his ten men, such as those shown at 11, in the spaces 9 and arranges them with their white surfaces exposed. In 85 proper turn the player moves his men in his spaces or in the spaces of his opponent, being restricted of course, to the movement of the men in the direction of the goal 2. The players are supposed to reach the spaces 90 17 in proper turn and in further turn the players reach the goal 2. At this time the player reverses his playing pieces or men upon the goal so as to expose the opposite designating color which will indicate that 95 a particular playing piece or man has succeeded in reaching the desired goal 2 and is on his return to the goal 4. As stated, each player is allowed to move his playing pieces to positions where he can jump the 100 pieces of his opponent and in so doing he is entitled to remove the pieces jumped by him from the board. The player succeeding in returning the greatest number of his playing pieces to the final goal is decided the 105 winner.

While the game board, as shown, is designed to present the appearance of a globe, in view of the intent of the game, it is obvious that the particular configuration of 110 the board is immaterial to the playing of the game, provided the arrangement of the

playing spaces remains as described. The sector like spaces 17 shown may be square or other suitable shape and it is understood that as the players of the game succeed in placing their playing pieces or men in these spaces, said pieces are in proper turn of the players placed in the goal 2.

I claim:—

10 In a game apparatus, a game board having straight longitudinal side edges and rounded ends, extensions representing the final goals formed on the said ends at the medial portions thereof, said extensions or final goals diverging outwardly beyond said ends, said board being divided into companion groups or distinguished playing spaces, and another goal, the latter mentioned goal being centrally located on the board, said groups merging inwardly from the opposite ends thereof in a direction toward the latter mentioned goal and communicating therewith, the said board being

also provided with intermediate spaces, dividing the said separate groups or spaces from each other on opposite sides of the 25 axial line of the board and the said companion groups or spaces being disposed adjacent to the centrally located goal, the said latter mentioned groups representing different courses of travel to and return from 30 the goal, and a plurality of playing pieces adapted to be arranged in the playing spaces of each group, the said playing pieces of one group being distinguished from the playing pieces of the other group, and the pieces for 35 each group being provided with differently colored parts, which are adapted to be exposed for the purpose specified.

In testimony whereof I affix my signature in presence of two witnesses.

JOHN H. ELVERS.
